(57) **CLAIM**

The ornamental design for flatware, as shown and described.

DESCRIPTION

FIG. 1 is a top plan view of a new and ornamental design for flatware embodied as a spoon, with the spoon portion shown in phantom for illustrative purposes only and forming no part of the claimed design;

FIG. 2 is a bottom plan view thereof;

FIG. 3 is a side elevation view thereof, the opposite side being a mirror image;

FIG. 4 is a cross-sectional view of a longitudinal portion of the handle taken along section line 4—4 of FIG. 1 to illustrate the shape of the handle portion that is the subject of the cross-section and with the interior construction details being illustrated in phantom lines and not forming any part of the claimed design;

FIG. 5 is an enlarged cross-sectional view taken along section line 5—5 of FIG. 1 to illustrate the exterior peripheral shape of the article at the cross-section and with the interior construction details being illustrated in phantom lines and not forming any part of the claimed design; and,

FIG. 6 is an enlarged cross-sectional view taken along section line 6—6 of FIG. 1 to illustrate the exterior peripheral shape of the article at the cross-section and with the interior construction details being illustrated in phantom lines and not forming any part of the claimed design.
